LUMINAIR

Thomas W. Rolph, Newark, Ohio, assignor to
Holephane Company, Inc., New York, N. Y., a
Corporation of Delaware

Application September 23, 1932
Serial No. 634,452

18 Claims. (Cl. 240—106)

The present invention relates to luminairs, and is more particularly directed toward luminairs employing refractors for light control. It relates to an improvement in refractors, and is of particular value for highway lighting but may also be used for other classes of lighting where a long narrow area is to be illuminated.

In the lighting of outdoor areas, such as streets and highways, it is customary to space the luminairs at considerable distances apart. Such spacing provides the greatest economy in cost of installation and operation, consistent with obtaining good lighting results. A spacing which is generally considered satisfactory is 8 times the 10 mounting height but other ratios of spacing to height varying widely from this are frequently used. Small spacing ratios in the neighborhood of 1 to 4 times the mounting height are rarely used and are uneconomical.

When a long narrow strip of roadway such as an interurban highway is illuminated, the light should be confined within a narrow lateral angle. If such a strip is lighted by units spaced at the customary distances apart, an attempt to spread 20 the light with reasonable uniformity over the area will result in very high candle-power toward the point midway between units. This candle-power will be much higher than is the case when light is distributed with reasonable uniformity 25 over wider roadways such as city streets. This 30 will be clear from an example.

If a luminair is so designed as to illuminate with reasonable approach to uniformity an area 35 70 ft. wide and 200 ft. long, the useful flux is distributed over 14,000 square feet. If the luminair is placed at the center of the area, the candlepower will be highest in the direction toward the edge approximately 100 ft. away. City streets are customarily 70 to 80 ft. wide but interurban 40 highways are usually much narrower, the two lane highway being 18 ft. to 20 ft. wide ordinarily. If a luminair is designed to illuminate this narrower roadway with the same light distribution as on the wider roadway, the light would 45 be confined to an area approximately 20 x 200 ft. and would be distributed over 4,000 square feet instead of 14,000 square feet. Therefore, the candlepower in all directions toward this area 50 will be higher in the ratio of

14000
4000

Out toward the extreme edge of the area, the candlepower is already high in the first case and 55 will become extremely high in the latter case.

Points on the street halfway between units are at high angles from the nadir of the luminair and high candlepower at such angles causes glare. It has been found desirable, in facing such a problem, to design the luminair to provide a certain 60 limited candlepower toward the extreme edge of the area or in other words toward the eye of an observer about halfway between luminairs. By limiting the candlepower to a certain maximum value in such directions, glare toward the eyes of 65 a motorist is kept sufficiently low to be innocuous.

Such limitation at the angle of maximum candlepower means that an excess of light is left to be delivered at other angles. The refractor will, therefore, be designed to deliver this excess light 70 to the area to be illuminated below the angle of maximum and to distribute the light properly over this area.

It will usually be found that when the illumination is non-uniform, the most desirable distribution provides the maximum illumination directly under the unit with gradually diminishing values to the minimum halfway between units. Such a distribution of illumination provides conditions which reveal nearby objects by direct 75 80 illumination and distant objects by silhouette as dark outlines against a lighter background. The light background in this case is the roadway which appears bright from a distance because of light reflected diffusely and specularly from the pavement.

This non-uniform distribution of light is not entirely satisfactory for direct illumination whereby objects are seen more completely than by silhouette. However, in highway lighting the 90 principal purpose of the lighting is to provide freedom from collision. Silhouette is quite satisfactory for this purpose. Other purposes of street lighting such as safety from attack and burglary, and convenience in recognizing passers-by, etc., which require a more uniform distribution of illumination are not of great importance in the lighting of interurban highways because such highways are primarily for the use of motorists rather than pedestrians. The motorist can 95 100 stop underneath a luminair if he desires intense illumination.

It is, therefore, desirable for narrow highways, to limit the candlepower of the maximum beam of light thus avoiding excessive glare and to 105 use the surplus light to build up the illumination beneath the luminair and at nearby points to a higher value than the illumination half-way between luminairs.

The accompanying drawings show a form of 110

two piece refractor provided with prisms for distributing light for roadway illumination, it being understood that the drawings are illustrative of the invention.

5 In these drawings:

Fig. 1 is a diagram showing important angles in a typical highway lighting installation,

10 Figs. 2 and 3 are light distribution curves. Fig. 2 showing lateral distribution about a vertical axis, and Fig. 3 vertical distribution through the main beam and across the street or road;

15 Fig. 4 is a vertical sectional view taken in a plane across the road or street (or the line 4-4 of Fig. 5), the inner piece of the refractor being largely shown in section;

Fig. 5 is a top plan view of the inner glass part to show the disposition of the prisms;

20 Fig. 6 is an elevational view of the outer glass part, the prisms being indicated in dotted lines;

25 Fig. 7 is a top plan view of the outer refracting member, showing the distribution of the vertical prisms therein;

30 Fig. 8 is a horizontal sectional view taken on the line 8-8 of Fig. 4 to illustrate the control 25 of light by the double vertical refracting prisms; and

35 Fig. 9 is a projection of a hemisphere, similar to a Mercator's projector, with light source at the center and important zones of light indicated.

40 In Fig. 1, a typical highway is shown with the luminair mounted a short distance in from one edge of the highway. The various vertical and lateral angles of light intercepted by the highway are shown in this illustration. It will be seen that in the vertical plane, running directly across the street, the light should be spread from about 20° back of the unit to about 50° out from the unit across the street. The maximum candle-power along the street would ordinarily be delivered at the 75° vertical angle, as indicated in full lines in Fig. 3. At this vertical angle, the lateral spread is from about 5° back of the unit out to about 20° out from the unit across the 45 street. The distribution at right angles to the curb line is indicated by the dotted curve of Fig. 3. It is clear that at the angle of maximum candle-power, a relatively small lateral spread (in this case 25°) is desirable for highway lighting. It has 50 been pointed out above that if the light available for distribution on the highway is distributed to give uniform illumination, the maximum candle-power in this relatively small lateral zone will be extremely high and to avoid this, the maximum candle-power should be limited and the additional light distributed along the highway below this angle.

55 The refractor for effecting the desired distribution of light is shown in the form of a two piece refracting bowl open at the top. The inner bowl 10 (Fig. 4) is smooth inside and carries vertical and horizontal prisms on the outer surface. The outer bowl 11 may be rippled on the outside and carries vertical prisms on the inner surface. 60 The inner bowl is made in a split mold having three 90° parts and two 45° parts, the dividing lines of the mold being indicated at M, N, O, P, Q, of Fig. 5. These mold lines form convenient limits for the horizontal prisms of different forms employed.

65 A large part of the half of the refractor which is toward the street (i. e. the part on the left of Figs. 4-9, inclusive) uses horizontal refracting prisms on the outer surface of the inner glass part as shown at A, and vertical refracting

70 prisms a on the inner surface of the outer glass part whereby light is concentrated at the desired vertical angle with the desired lateral spread, and light is also distributed below this vertical angle with a continually increasing spread as the vertical angle decreases. The refracting prisms A extend from M to N and from O to P for the entire height of the refractor and occupy the lower part of the refractor between N and O. The house side of the outer refractor is provided with vertical refracting prisms a' which extended the entire height of the refractor. These prisms act 80 on light received through prisms A to direct it lengthwise of the road with the desired vertical angle and lateral spread. This zone is designated as Aa in Fig. 9. Near the bottom of this portion of the refractor, both the horizontal and vertical prisms become very shallow or may be omitted since little light redirection is necessary.

85 On the right-hand portion or house side of the inner refractor a certain zone B extending from M to P carries reflecting prisms designed to return the light back through the light source to be handled by the prisms below the light source in zone A on the opposite side. This is indicated 90 by the ray 12 in Fig. 4. Zone C of the inner refractor is made up of vertical, totally reflecting prisms. These vertical, totally reflecting prisms do not return the light back on its own path as the horizontal, totally reflecting prisms do. The 95 vertical prisms reflect the light in the same way that a mirror would reflect it with the angle of reflection equal to the angle of incidence. Since the top of these prisms is on a level with the light source and the prisms extend downward 100 from this point, all light reflected from them is directed across the reflector below the light source. This light is handled by the refracting prisms on the opposite side of the refractor and distributed over the street area at angles below the angles 105 at which the direct light is distributed. In this particular case a small section of these vertical reflecting prisms is preferable to the continuation of the band of horizontal reflecting prisms because the latter would tend to reflect light back 110 to reflecting instead of refracting prisms on the opposite side of the refractor.

115 The house side of the inner refractor 10 has a series of vertical prisms D extending from M to Q and a similar series D' extending from Q to P, of opposite sign, these prisms being placed below the totally reflecting prisms C. The street side of the inner refractor has, near the top, a series of totally reflecting prisms E, similar to the prisms 120 B, and acting on light as indicated by the ray 125 13. This reflected light, as well as certain direct light, is received by the vertical prism bearing zones D-D'. The prisms D-D' are opposite vertical prisms a' carried by the outer refractor 130 part 11. This prism arrangement makes it possible to obtain a much greater lateral deviation of light than can be obtained with vertical prisms on a single surface. It is possible to use this new 135 feature of double vertical prisms giving great lateral deviation to the light, because the particular distribution of light required, as pointed out above, does not need vertical redirection of light which is emitted from the light-source below the angle of maximum, in this case 75°. The problem is to get this light onto the highway at 140 any angle below the angle of maximum. Double vertical refracting prisms will do this more efficiently than constructions which have been used 145 in the past.

150 The high efficiency with which light in this

zone D—D' can be handled makes possible the use of a second zone of reflecting prisms E on the upper part of the opposite side of the refractor. This zone receives light at angles which make redirection by refraction to useful directions difficult. By using reflecting prisms in this zone, light will be directed back (as above referred to) toward the light source to be handled by the efficient double set of refracting prisms in zone D on the opposite side.

Fig. 9 is given to show in diagrammatic form these relative zones and the distribution of light required. This figure is a projection (similar to Mercator's) of a hemisphere with the light-source at the center and the various lateral and vertical angles designated. The vertical angles run from 0°, the nadir, through 90°, the horizontal, to 180°, the zenith. The lateral angles run from 0°, which is directly across the street from the luminair, through 90°, which is parallel to the direction of the street, to 180°, which is directly back away from the street.

The light distribution required as illustrated in Fig. 1 is shown by the area F in this diagram. The area of the refractor which carries the customary combination of horizontal and vertical refracting prisms is shown by area Aa. This corresponds to area A of Fig. 2. The reflecting prisms in area B of Figs. 4 and 5 are indicated as area B in this diagram. The double vertical reflecting prisms which form a new feature in refractor construction are used in area D. The horizontal reflecting prisms used in area E are made possible by the use of the double vertical prisms in area D.

Theoretically no redirection of light is necessary in area F but actually prisms in sections Aa and D may extend over into area F in order to obtain the most effective distribution of light within the zone to be illuminated.

It should be understood that the angles shown in the diagrams and referred to herein are typical angles of a certain condition met with in illuminating highways. The invention may be used to obtain distributions varying considerably from this example. The zones using the different types of prisms indicated may be changed considerably in relative size and position. Therefore, the invention must not be considered as limited to this particular example.

In the drawings a 2-piece refractor is shown with prisms on the outside surface of the inner piece and on the inside surface of the outer one. It will be clear that two pieces are not necessary. Such construction is preferred because better results can thereby be obtained, but the invention may also be applied to single-piece refractors using prisms on both the inner surface and the outer surface, co-operating in the same general manner as when two pieces are used.

It is obvious that the invention may be embodied in many forms and constructions, and I wish it to be understood that the particular form shown is but one of the many forms. Various modifications and changes being possible, I do not otherwise limit myself in any way with respect thereto.

What is claimed is:

1. A refractor, one section of which concentrates light vertically and laterally, while another section concentrates light laterally only, by means of two sets of parallel prisms carried on opposed surfaces of the refractor.

2. A refractor whose principal prismatic construction is divided horizontally into two parts,

the upper part carrying horizontal prisms on one surface and vertical prisms on an opposed surface and the lower part carrying vertical prisms on one surface and additional vertical prisms on an opposed surface.

80

3. A refractor, the upper part of which is adapted to produce concentration of light in both vertical and lateral directions, and the lower part of which is adapted to produce concentration of light in lateral directions only, by means of two sets of vertical prisms disposed on opposed surfaces of the refractor.

85

4. A refractor whose principal prismatic construction is divided into two parts, the lower part carrying vertical prisms on one surface and additional vertical prisms on an opposed surface while the upper part is divided into sections some of which carry vertical prisms on one surface and horizontal prisms on an opposed surface while others carry reflecting prisms adapted to return light to the lower section of the refractor for action by the prisms thereon.

90

5. A refractor adapted to concentrate light at a predetermined angle and carrying a double set of vertical prisms disposed on opposed surfaces of the refractor and adapted to control light emitted by the light-source below this angle.

95

6. A refractor adapted to give a moderate concentration of light at a predetermined angle below the horizontal, the distribution of light being accomplished by controlling light from the source emitted above this angle by means of horizontal prisms on one surface of the refractor and vertical prisms on an opposed surface of the refractor, while light from the source emitted below this angle is controlled by vertical prisms on one surface of the refractor and additional vertical prisms on an opposed surface of the refractor.

100

7. A luminair comprising a light-source and a light-controlling enclosure, one section of which carries means for reflecting light onto an opposite section, which transmits both direct and reflected light, and refracts it by means of a double set of parallel prisms disposed on opposed surfaces of the transmitting section.

105

8. A luminair comprising a light-source and a light-controlling enclosure, one section of which carries means for reflecting light back toward the light-source, while another section carries means for concentrating light in both vertical and lateral directions and a third section carries means for concentrating light in lateral directions only.

110

9. A luminair comprising a light-source and a light-controlling enclosure, one section of which carries means for reflecting light back toward the light-source, while another section carries prisms for concentrating light by refraction in both vertical and lateral directions and a third section carries prisms for concentrating light by refraction in lateral directions only.

115

10. A luminair comprising a light-source and a light-controlling enclosure, one section of which carries prisms for reflecting light back toward the light-source, while another section carries prisms for concentrating light by refraction in both vertical and lateral directions and a third section carries prisms for concentrating light by refraction in lateral directions only.

120

11. A luminair comprising a light-source and a light-controlling enclosure, one section of which carries means for reflecting light back toward the light-source, while another section carries means for concentrating light in both vertical and lateral directions and a third section carries two sets of vertical prisms disposed on opposed surfaces of the refractor.

125

130

135

140

145

150

- parallel refracting prisms disposed on opposed surfaces of the enclosure and adapted to concentrate light in lateral directions.
12. A luminair for road lighting and adapted to be mounted above the road, the luminair comprising a refractor having opposed vertical and horizontal prisms for producing beams of light concentrated in both vertical and lateral directions and directed obliquely downward toward the road surface, reflecting prisms on the upper "house" side of the refractor for reflecting light downwardly toward refracting prisms on the lower "street" side of the refractor which transmit this light as well as direct light downwardly toward road surface adjacent the luminair to increase the intensity of illumination in this region. 80
13. A luminair for road lighting and adapted to be mounted above the road and to one side of the center thereof, the luminair comprising a refractor having opposed vertical and horizontal prisms for producing beams of light concentrated in both vertical and lateral directions and directed obliquely downward toward the road surface, reflecting prisms on the upper "street" side of the refractor for reflecting light downwardly toward opposed vertical prisms on the lower "house" side of the refractor which refract the reflected light as well as direct light laterally for building up the intensity of the main beams of light and preventing intense illumination of the region on the house side of the luminair. 85
14. A luminair for road lighting and adapted to be mounted above the road and to one side of the center thereof, the luminair comprising a refractor having opposed vertical and horizontal prisms for producing beams of light concentrated in both vertical and lateral directions and directed obliquely downward toward the road surface, reflecting prisms on the upper "house" side of the refractor for reflecting light downwardly toward refracting prisms on the lower "street" side of the refractor which transmit this light as well as direct light downwardly toward road surface adjacent the luminair to increase the intensity of illumination in this region, the refractor having reflecting prisms on the upper "street" side of the refractor for reflecting light downwardly toward opposed vertical prisms on the lower "house" side of the refractor which refract the reflected light as well as direct light laterally for building up the intensity of the main beams of light and preventing intense illumination of the region on the house side of the luminair. 90
15. A luminair for road lighting comprising a light source and a refractor, the refractor having in one quadrant on the "house" side thereof totally reflecting horizontal prisms above the light source and opposed vertical prisms below the light source and of opposite sign with respect to the center of the quadrant, and horizontal refracting prisms extending throughout the other three quadrants except for a region of totally reflecting horizontal prisms on the "street" side above the light source and opposite the vertical prisms, and vertical prisms to receive the light from the horizontal refracting prisms and condense it into two narrow beams directed lengthwise of the road. 95
16. A luminair for road lighting comprising a light source and a refractor, the refractor having in one quadrant on the "house" side thereof totally reflecting horizontal prisms above the light source and opposed vertical prisms below the light source and of opposite sign with respect to the center of the quadrant, and horizontal refracting prisms extending throughout the other three quadrants except for a region of totally reflecting horizontal prisms on the "street" side above the light source and opposite the vertical prisms, and vertical prisms to receive the light from the horizontal refracting prisms and condense it into two narrow beams directed lengthwise of the road, the vertical prisms on the "street" side of the refractor extending only through the upper part of the refractor so that refracted light may fall on the road surface at angles below the maximum without lateral deviation. 100
17. A luminair comprising a light source and a light controlling prismatic enclosure by which a portion of the light emitted from the source is concentrated both vertically and laterally at a predetermined angle and another portion of the light emitted by the source is concentrated laterally at lower angles. 110
18. A luminair comprising a light source and a light controlling prismatic enclosure in which light emitted by the source above a predetermined angle is concentrated at that angle and light emitted by the source below the predetermined angle is concentrated laterally below that angle. 115
